UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. 7,139, dated January 27, 1874; application filed December 11, 1873.
[Term of Patent 14 years.]

A.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the lower or main portion of the casing of a soda-water apparatus, which is of rectangular form. From the center of the portion A rises a rectangular portion or tower, B, which is surmounted by an ornamental cap, a. On each side of the tower is an incline, b, extending from the wall c to the flat top d of the end of the portion A. At each corner of the casing is an ornamental projection, e, extending out from the end, and contiguous thereto, at each corner of the front and rear sides, is an ornamental pilaster, f, the

design thus produced being unique and ornamental.

What I claim as my invention, and desire to secure by Letters Patent, is—

1. The design for the casing of a soda-water apparatus, consisting of the rectangular portion A, with its central elevated portion B, substantially as herein shown and described.

2. In combination with the casing of a soda-water apparatus, the design of the ornamental projections e at the corners of the portion A, as shown.

3. In combination with the casing of a soda-water apparatus, the design of the ornamental pilasters f, as shown.

Witness my hand this 3d day of December, A. D. 1873.

GEO. F. MEACHAM.

In presence of—

P. E. TESCHEMACHER,
JOHN E. PIERCE.
